EDSON L. YAW, OF BROOKSVILLE, FLORIDA, ASSIGNOR TO JENNIE M. YAW

BRUSH, BRAMBLE, GRASS, VINE, AND CORN CUTTER AND SHEARER

Application filed December 8, 1928. Serial No. 324,727.

This invention relates to hand instruments used for cutting vegetation and particularly to the type of cutter ordinarily used by being swung substantially in line with the arm. 5 Among the objects of the invention are the production of an improved form of handle enabling the device to be swung efficiently with much less fatigue than results from the use of a straight, smooth handle, and the provision of a stronger, heavier, more flexible, and less breakable frame member of metal than those hitherto in use.

With the hand in the loop as described, the force of the impact when the cutting tool 15 strikes the weeds or other vegetation is received with a relatively rigid arm, and the tool does not revolve in the hand toward the end of the stroke, because the wooden handle lies against the wrist to prevent this undesirable lost motion.

The muscular tension required to retain the grasp on the ordinary straight, smooth, wooden handle used with cutters of a similar type in the prior art, is fatiguing with a tool of 25 sufficient weight to provide the proper inertia, but in holding the present tool with the hand through the loop, this continued tension is not necessary. If desired, the tool may be used with both hands on the wooden handle, or with one hand on the handle and the other in the loop for heavy work, while with 30 light work, the tool may be grasped by the wooden handle with one hand.

Below the portion 3, the strips 1 and 2 35 diverge to make room for a cutting blade 13, preferably sharpened on both edges as indicated in Fig. 1. These divergent legs are twisted, preferably in oppositely rotating spirals, as shown in Fig. 2, for the major 40 part of their length. In Fig. 6, the lower end of the strip 1 is shown as bent inward at 14 and perforated for the bolt 15 which secures the blade 13 to the strip with the plane of the blade transverse to the axis of 45 the instrument. Fig. 7 shows a stronger construction in which two bolts 16 are used. It is customary in tools of this type to make one leg longer than the other without any provision for adjustment. The user swings the 50 tool with the axis of the frame at a consider-

able angle to the vertical, with the blade far enough away to avoid touching his feet, but because of the outer leg of the tool being longer, the edge of the blade will still be held parallel to the ground, as in Fig. 2. 55

In the drawings forming a part of this specification, Fig. 1 is an elevation and Fig. 2 a side view of a typical embodiment of the invention; Fig. 3 is a detail, partly in section and on a larger scale, of the handle shown 60 in Fig. 2; Figs. 4 and 5 are fragmentary views illustrating alternative forms of handle loops; and Figs. 6 and 7 are fragmentary views showing alternative ways of connecting the cutting blade to the lower end of the frame. 65

The frame member consists of two substantially flat metallic strips, 1 and 2, placed with a flat surface of one against a flat surface of the other and twisted together to form an axially arranged straight central portion 3, the strips preferably being held together by some suitable fastening means, such as the rivets 4 and 5, or their equivalents. Above the portion 3, the strips are both bent outwardly, in opposite directions and then brought inward to form a loop 6 having its major axis extending transversely of the axis of the portion 3. Above the loop, the strips are set substantially parallel and spaced to receive a wooden handle 7 arranged longitudinally of the main axis of the instrument. As shown in Fig. 3, the handle may be recessed on its opposite sides to receive the ends of the strips, which are perforated as at 8 for fastening means such as the screws 9 or the rivets 10 shown in Figs. 4 and 5. The metallic strips thus reinforce the wooden handle and are substantially flush with its outer surface, presenting no projections to hurt the hands of the user. 75 80 85 90

The loop 11 of Fig. 4 and the loop 12 of Fig. 5 represent mere variations in design, the dimensions in all cases being such as to permit the easy insertion of the hand with the palm upward, so that the wrist may be held straight with the wooden handle lying against it as the tool is swung with a full-arm movement about the shoulder as a pivot. 95

As a means for adjusting the effective length of the outer legs, an extension member 100

17 is shown in Fig. 2, bent at its lower end in a manner similar to the bending of the end of the strip 1 in Fig. 6 and having its upper portion perforated for a bolt 18 which 5 may be engaged within any of a series of perforations 19 in the straight lower end of the strip 2. Any desired element, as a blade, rake, scuffle hoe, potato digger, or fork, may thus be set transversely at substantially right 10 angles to the axis of the frame, as indicated in broken lines at 20 in Fig. 2.

It will be understood that the details shown are merely illustrative and that many changes in form, proportions, and arrangements of 15 parts may be made without departing from the scope of the invention as set forth in the claims.

I claim:

1. A hand instrument comprising a handle 20 extending longitudinally of the main axis of the instrument, a loop adjacent to the handle and extending transversely of the axis, the loop being of a size to receive the hand, a frame member consisting of two metallic 25 strips twisted together from the loop to a point substantially midway of the length of the instrument and thence diverging to the end of the instrument remote from the handle, and an implement secured between the 30 separated ends of the strips.

2. A hand instrument comprising a longitudinally arranged handle, a pair of metallic strips secured upon opposite sides of the handle, the strips being bent to form a hand loop 35 adjacent to the lower end of the handle when the instrument is in normal position for use, the strips being secured together for approximately half their length and then diverging to receive therebetween an implement, and an 40 implement secured at its ends to the ends of the strips.

3. A hand instrument comprising a handle extending axially of the instrument, a hand loop at the normally lower end of the handle 45 arranged with its greatest dimension transversely of the axis, a frame member consisting of two metallic strips twisted together axially of the instrument for approximately half their length and then diverging, and a 50 sharp-edged blade secured at its ends to the ends of the strips, the plane of the blade being transverse to the axis of the instrument.

4. A cutting tool intended for use by being swung substantially in line with the arm, 55 which comprises a longitudinally arranged handle at the upper end of the tool, a hand loop to permit the insertion of the hand, palm upward, adjacent to the base of the handle, a frame member adjacent to the loop comprising 60 two metallic strips united and made rigid by twisting about a common axis for approximately half their length and diverging at their lower ends, and a cutting blade set with its plane transverse to the axis of the tool and with its longitudinal axis in substantially 65

the same plane with the major axis of the hand loop, the blade being secured to the ends of the strips.

5. A tool as in claim 4 having means for adjusting the angle of the plane of the blade 70 by changing the effective length of one of the strips.

6. A hand instrument comprising a frame member consisting of two substantially flat metallic strips placed with a flat surface of one adjacent to a flat surface of the other, and twisted together for approximately half their 75 length and then diverging, and an implement detachably secured between the separated ends of the strips.

7. A hand instrument comprising a frame member consisting of two substantially flat metallic strips placed with a flat surface of one adjacent to a flat surface of the other, and twisted together for approximately half their 80 length and then diverging, an implement detachably secured between the separated ends of the strips, and a fastening means securing the metallic strips tightly together at the point where they diverge.

In testimony whereof, I have hereunto signed my name on this 24th day of November, A. D. 1928.
